(57) **CLAIM**

The ornamental design for a laptop computer as shown and described.

DESCRIPTION

FIG. 1 is a front view of a laptop computer showing the new design;

FIG. 2 is a back view thereof;

FIG. 3 is a left side view thereof;

FIG. 4 is a partial enlarged view of FIG. 3;

FIG. 5 is a right side view thereof;

FIG. 6 is a top view thereof;

FIG. 7 is a bottom view thereof;

FIG. 8 is a perspective view thereof;

FIG. 9 is a partial enlarged view of FIG. 6;

FIG. 10 is another partial enlarged view of FIG. 6;

FIG. 11 is a partial enlarged view of FIG. 8; and,

FIG. 12 is another partial enlarged view of FIG. 8.

The broken lines shown in the drawings illustrate portions of the laptop computer that form no part of the claimed design. The double dot-dash broken lines shown in the drawings indicate the outer limits of portions of figures shown enlarged and form no part of the claimed design.

The speaker grills on either side of keypad are shown in broken lines and form no part of the claimed design.

Unshaded surfaces form no part of the claimed design.

The dot dash broken line in FIG. 7 depicts a boundary of the claimed design and forms no part thereof.

1 Claim, 10 Drawing Sheets

Related U.S. Application Data

division of application No. 35/507,695, filed on Jun. 25, 2019 (U.S. filing date under 35 U.S.C. 384), and having an international filing date of Jun. 25, 2019, now Pat. No. Des. 914,669.
